(57) **CLAIM**

The ornamental design for a bench, as shown and described.

DESCRIPTION

FIG. 1 is an isometric view of a bench in accordance with the new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof; and,

FIG. 7 is a bottom view thereof.

The broken lines shown represent portions of the bench that form no part of the claimed design.
